UNITED STATES PATENT OFFICE

JOHN D. SMID, OF WICHITA, KANSAS

SHELVING

Application filed September 27, 1928. Serial No. 308,834.

This invention aims to provide a shelving which can be taken down and set up readily, it being possible to extend the shelving as far as occasion may demand.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:—

Figure 1 shows an elevation, a device constructed in accordance with the invention;

Figure 2 is a top plan;

Figure 3 is a section on the line 3—3 of Figure 1;

Figure 4 is a section on the line 4—4 of Figure 1;

Figure 5 is a horizontal section taken through one of the top rails, parts being broken away;

Figure 6 is a composite perspective view illustrating sundry parts of the shelf, parts being broken away.

The device forming the subject matter of this application preferably is made of metal throughout. It includes standards 1. Each standard 1 may be made of a bar having lateral extensions 2 connected by straight arms 3. The bar is bent on itself as at 4, to form a foot, the arms 3 being brought into contact with each other, and the extensions 2 being brought opposite to each other to form seats or openings 5. The arms 3 may be joined together, if desired, by spot welding, or in any other suitable way.

Tubular top rails 6 are provided and are supplied in their undersides with openings 7 through which the upper ends 8 of the standards 9 pass, as shown in Figure 5, the top rails 6 resting on the upper ends of the

standards. On the extreme outer ends of the rails 6, caps 9 may be held, removably, by headed pins 10, or otherwise. The top rails 6 may be joined together by sleeves 11 and headed pins 12, removably, as indicated in Figure 5, so that one bank of shelves may be connected to another bank of shelves, as disclosed in Figure 1, it being possible in this way to provide as long a stretch of shelving as the merchant may desire.

Any desired number of shelves 14 are supplied. Each shelf 14 is made up of a plurality of strips 15 disposed edge to edge, the strips having underlying eyes 16 at their ends. The eyes 16 of the several strips in each shelf are lined up, and the strips 15 are held together by transverse binders 17 provided at their ends with hooks 18 that engage along the edges of the outermost strips 15.

The holes 21 in the eyes 16 are of about the same diameter as the seats or openings 5 in the standards 1. The shelves 14 are placed between the standards 1, the openings 21 in the shelves being alined with the seats 5 in the standards 1. Then cross members or rods 19 are pushed into place endwise, the projections 20 being short enough so that this can be done. When the weight of the shelves 14, however, comes on the cross members 19, the cross members 19 are held down in the seats 5 of the standards 1, and the projections 20 prevent the rods or cross members from pulling out endwise.

The device is simple in construction, but is so made that it can be set up and taken down readily. Shelving constructed in accordance with the invention can be kept clean and free from vermin and dirt at all times.

Having thus described the invention, what is claimed is:—

1. In a device of the class described, a shelf made up of like, interchangeable strips, located side by side and provided at their ends with eyes, cross members insertable through the eyes and having lateral projections at their ends, standards having openings through which the ends of the cross

members are inserted, the ends of the cross members being movable transversely in the openings of the standards, to cause the projections to engage with the standards, the strips having their longitudinal edges in contact, and the eyes being as wide as the strips, thereby to form continuous tubular passages through which the projections may move without catching, when the cross members are inserted through the eyes, the openings of the eyes being of greater diameter than the cross members, and of sufficient diameter to permit the passage of the projections, and means for holding the strips together.

10 2. In a device of the class described, a shelf made up of strips located side by side and provided at their ends with eyes, cross members insertable through the eyes and having lateral projections at their ends, standards having openings through which the ends of the cross members are inserted, the ends of the cross members being movable transversely in the openings of the standards, to cause the projections to engage with the standards, the strips having their longitudinal edges in contact, and the eyes being as wide as the strips, thereby to form continuous tubular passages through which the projections may move without catching, when the cross members are inserted through the eyes, the openings of the eyes being of greater diameter than the cross members, and of sufficient diameter to permit the passage of the projections, and means for holding the strips together, said means comprising binders extended transversely of the strips on the outer surface of the strip and supplied with hooks engaged around the edges of the outermost strips.
